(57) **CLAIM**

The ornamental design for a fishing net with ball-in-cup retention clip assembly, as shown and described.

DESCRIPTION

FIG. 1 is a front perspective view of the fishing net with its telescopic handle retracted;

FIG. 2 is a top plan view of the fishing net from FIG. 1;

FIG. 3 is a bottom plan view of said fishing net;

FIG. 4 is a right side view of the fishing net from FIG. 1, the left side view being a mirror image of same;

FIG. 5 is a front view of the fishing net from FIG. 1 looking longitudinally along the telescopic handle end;

FIG. 6 is a rear view of the fishing net looking longitudinally from the opposite end of FIG. 5;

FIG. 7 is an upper perspective view of cup retention clip for one embodiment of clip assembly according to this invention; FIG. 8 is an exploded view of said cup retention clip assembly showing its various components;

FIG. 9 is a front view of the whole clip assembly from FIG. 7; FIG. 10 is a rear view of said clip assembly;

FIG. 11 is a left view of said clip assembly, it being understood that the opposite, right plan view is a mirror image of same;

FIG. 12 is a top plan view of said clip assembly;

FIG. 13 is a bottom plan view of said clip assembly; and

FIG. 14 is a side perspective view showing the ball of the fishing net situated over the clip assembly; FIG. 15 is a side perspective view showing the ball of the fishing net situated most of the way into said clip assembly; and,

FIG. 16 is a side perspective view showing the ball of the fishing net “locked” into the bottom of said clip assembly for transport.
